UNITED STATES PATENT OFFICE.

ESERY LAYEUX, OF MINNEAPOLIS, MINNESOTA, ASSIGNOR OF ONE-HALF TO FRANK J. KERNER, OF MINNEAPOLIS, MINNESOTA.

SIDE-DOOR STRUCTURE FOR CARS.

1,332,989.

Specification of Letters Patent. Patented Mar. 9, 1920.

Application filed April 8, 1918. Serial No. 227,216.

To all whom it may concern:

Be it known that I, ESERY LAYEUX, a citizen of the United States, residing at Minneapolis, in the county of Hennepin and

5 State of Minnesota, have invented certain new and useful Improvements in Side-Door Structures for Cars; and I do hereby declare the following to be a full, clear, and exact description of the invention, such as will 10 enable others skilled in the art to which it appertains to make and use the same.

My invention relates to improvements in side door structure for cars; and, to this end, it consists of the novel devices and combinations of devices hereinafter described and defined in the claims.

In the accompanying drawings, which illustrate the invention, like characters indicate like parts throughout the several 20 views.

Referring to the drawings:

Figure 1 is a fragmentary perspective view of a car body, equipped with the improved side door structure;

25 Fig. 2 is a fragmentary vertical section, taken through the car body, at the door opening, and centrally through the door structure;

Fig. 3 is a view corresponding to Fig. 2, 30 with the exception that the main door is shown partly in edge elevation and partly in section to expose the grain door and one of its hangers;

Fig. 4 is a fragmentary inside view of the 35 door structure;

Fig. 5 is a detail view, in section, taken on the line 5—5 of Fig. 1, with the door structure closed;

Fig. 6 is a fragmentary detail view in out- 40 side elevation, illustrating one of the clamping bolts;

Fig. 7 is a detail view, in section, taken on the line 7—7 of Fig. 1, with the door closed;

45 Fig. 8 is a view corresponding to Fig. 7, but illustrating a modification of the separable keeper bracket; and

Fig. 9 is a perspective view of the parts shown in Fig. 8.

The numeral 10 indicates a car body, having in its side the usual door opening 11. An overhead track rail 12 is secured to the car body 10, above the door opening 11, and extending to one side thereof. At the other side of the door opening 11, a vertical door stop strip 13 is secured to the car body, but

spaced apart from said door opening, for a purpose that will presently appear.

The improved door structure comprises a main door 14, a supplemental door 15, and a grain door 16. The main door 14, as shown, 60 has a marginal frame 17, constructed of angle bars, and is suspended by roller equipped hangers 18, from the track 12 to have a sliding movement to and from a position to close the door opening 11. The 65 supplemental door 15 is provided for closing an opening in the top of the main door 14, through which opening access may be had to the car, when the main door is closed, either for the purpose of inspecting the contents 70 thereof or loading the car with grain. This supplemental door 15 is hinged, at its upper edge, to the main door 14, so as to close under the action of gravity. Any suitable means may be provided for locking or holding 75 the supplemental door 15 closed.

The main door 14 is recessed, below the supplemental door 15 and between the in-turned flanges of its frame 17, to form an inside pocket 19, to receive the grain door 80 16. A marginal frame 20, of angle bars, like the frame 17, for the main door 14, is also, as shown, preferably provided for the grain door 16. A pair of long hanger bars 21 is provided for suspending the grain 85 door 16 from the main door 14 for lateral swinging movement toward and from the car body 10, within the pocket 19. The upper ends of these hanger bars 21 are pivoted at 22 to the adjacent inturned flanges of the 90 main door frame 17, and the lower ends thereof are pivoted at 23 to the flanges of the frame 17, which form the vertical edges of the grain door 16. It is highly important to note that the vertical and lower edges 95 of the grain door 16 overlap the car body 10, at the sides and bottom of the door opening 11, when the main door 14 is closed.

To move the grain door 16 laterally in the pocket 19, for clamping the same against the car body 10, to seal the door opening 11 below the supplemental door 15, I connect the main and grain doors by a multiplicity of clamping bolts 24. These bolts 24 are inserted through bores in the vertical and lower 105 members of the frames 17 and 20, with their heads exposed, so that they may be turned from the outside of the car body. As shown, the heads of the bolts 24 are countersunk by depressing the outer flanges of the frame 17 110

of the main door 14, to form seats 25, having sufficient diameter to permit a wrench to be applied to said heads. The bolts 24 are held against endwise movement in the 5 main doors 14 but with freedom for turning movement in respect thereto by securing collars 26 to said bolts inward of the seats 25. The inner ends of the bolts 24 have screw threaded engagement with nut blocks 10 secured to the grain door 16. The bolts 24 are preferably provided with left hand screw threads so as to move the grain door 16 into clamping position against the car body 10, when said bolts are turned to the right. 15 To afford a base of reaction for the main door 14, under the action of the bolts 24, in clamping the grain door 16 against the car body 10, I provide for the front, rear and lower edges of said main door keeper brackets 28, 29 and 30. The keeper brackets 28 are in the form of flat vertically spaced clips secured to the stop strip 13, and the keeper brackets 30 have a Z shaped formation, and are secured to the car body 10, below the 25 door opening 11. The keeper brackets 29, of necessity, comprise separable elements to permit the door structure to be moved edge-wise to and from a closed position. Each of these keeper brackets 29 comprises a flat 30 plate 31, secured to the rear edge of the main door 14, and projecting into a horizontal channel 32, formed in the car body 10, and extending rearward from the door opening 11. The other element of each 35 keeper bracket 29 is in the form of a cam finger or pin 33, anchored to the car body 10 and projecting into the respective channel 32. During the final closing movement of the door structure the cam pins 33 enter 40 apertures in the keeper plates 31, as best shown in Fig. 7.

Obviously, by turning the bolts 24 in the proper direction the grain door 16 may be clamped against the car body at the door opening 11, to form tight joints therewith at the vertical and lower edges of said door, and thus prevent the leakage of all kinds of grain. The keeper brackets 28, 29 and 30 will securely hold the main door 14 against 45 the outward pressure of the bolts 24. To unload a car of grain the bolts 24 are turned in a direction to draw the grain door 16 away from the car body and into the pocket 19. With the grain door 16 moved away 50 from the car body, the grain at the door opening will escape through the port 34, thus relieving the pressure on the grain door and permit the door structure to be easily 55 opened for the purpose of unloading the balance of the car. Preferably, as shown, the heads of the bolts 24 are made of peculiar shape, and by countersinking them a socket wrench of special design must be used 60 for turning the bolts to move the grain door, thus making it difficult for unauthorized 65 persons to tamper with the contents of the car.

Referring now to the modification shown in Figs. 8 and 9, the separable keeper bracket 35 is especially adapted for use on old cars, 70 and takes the place of the separable brackets 29. This bracket 35 comprises a fixed lug 36, on the rear edge of the main door 14, and is notched to receive and hold a loop-like member 37, anchored to the car body 75 10 by an eye bolt 38. When the keeper bracket member 37 is turned out of interlocking engagement with the fixed member 36, the same enters a recess in the car body 10 so as to not interfere with the opening and 80 closing movement of the door structure.

What I claim is:

1. The combination with a car body having a door opening, of a main door having an inside pocket and mounted for sliding 85 movement to and from a position to close said door opening, a grain door, said grain door having lapping joints with the car body at the sides and bottom of its door opening when the main door is closed, 90 clamping devices between the main door and grain door for pressing said grain door against the car body, and a relief port in the bottom of said pocket that is opened by a lateral movement of the grain door away 95 from the car body to permit the escape of grain from the car body when the door opening is closed by the main door.

2. The combination with a car body having a door opening, of a main door having an inside pocket and mounted for sliding movement to and from a position to close 100 said door opening, a grain door, said grain door having lapping joints with the car body at the sides and bottom of its door opening when the main door is closed, clamping devices between the main door and grain door for pressing said grain door against the car body, a horizontal channel in the car body extending rearward from its door opening, and a cam pin in the forward end of said channel, said main door having on its rear edge an extension working in said channel and provided with an aperture to receive the cam pin during the final closing movement of the main door to draw the same 110 toward the car body and hold the same against lateral movement therefrom.

3. The combination with a car body having a door opening, of a main door having 120 an inside pocket and mounted for sliding movement to and from a position to close said door opening, a grain door, vertical links supporting the grain door in said pocket from the main door for lateral swinging movement toward and from the car body, said grain door having lapping joints with the car body at the sides and bottom of its door opening when the main door is closed, clamping bolts secured to the main 125 130

door at its front, rear and bottom edge portions, and nut blocks secured to the grain door with which said clamping bolts have screw threaded engagement for imparting lateral movement to the grain door with respect to the main door and pressing said grain door against the car body.

In testimony whereof I affix my signature in presence of two witnesses.

ESERY LAYEUX.
